UNITED STATES PATENT OFFICE.

THOMAS FERNELEY WILEY, OF RAWDON, NEAR LEEDS, ENGLAND.

APPARATUS FOR WATERPROOFING TEXTILE FABRICS.

SPECIFICATION forming part of Letters Patent No. 416,388, dated December 3, 1889.

Application filed September 24, 1888. Serial No. 286,212. (No model.)

To all whom it may concern:

Be it known that I, THOMAS FERNELEY WILEY, a subject of the Queen of Great Britain, residing at Rawdon, near Leeds, England, have invented certain Improvements in an Apparatus for Waterproofing Textile Fabrics or Rendering them Water-Repellent, of which the following is a specification.

This invention consists of an apparatus for waterproofing textile fabrics or rendering them water-repellent by the application of waterproofing or water-repelling substances, agents, or compounds in the molten or melted state without solvent and afterward subjecting such fabrics to heat.

I apply any waterproofing or water-repelling substance, agent, or compound in the manner which is capable of being reduced to the molten state or melted by a temperature below what would damage the fabrics, of which the following substances are good examples: stearine, spermaceti, ozocerite, paraffine-wax, and Japanese wax, or other similar substances. These substances may be either separately applied or in combination.

In the accompanying drawings, Figure 1 represents a longitudinal section of a machine for applying waterproofing or water-repelling substances in the molten state to textile fabrics. Fig. 2 is a plan view of the same.

The machine containing my invention is represented in conjunction with an ordinary cylinder drying-machine, the feed end of which is shown, as such machines are particularly adapted to draw the fabrics through the waterproofing-machines as well as subsequently heat them; but it is obvious that other means may be employed for these purposes.

A trough A, containing the waterproofing or water-repelling substance, is fixed between frames B of the cylinder drying-machine, and the first of the heated cylinders C', revolving therein, melts said substance, and the periphery of said cylinder is therefore coated with it. The fabrics D to be operated upon are carried upon the reel E, mounted in bearings F, formed in the standards G, fixed on the end of each side frame B. Such standards also support adjustable tension-bars H and a top roller J. The fabrics D are connected to a "wrapper" previously passed through the drying-machine, and are thereby drawn from

the reel E round the tension-bars H, over the top roller J, and between the cylinder C' and the roller K. The roller K is adapted to press the fabrics against the cylinder C', thus depositing the waterproofing substances carried on the periphery of such cylinder upon said fabrics, which absorb it as they pass through the cylinder drying-machine. The amount of waterproofing substance thus deposited upon the fabrics depends upon the speed at which the cylinder C' revolves relative to the speed the fabrics are drawn into the drying-machine. To regulate this a toothed wheel L is mounted upon the arbor of the cylinder C', connected by the wheels M and N to the spur-wheel O, secured on the arbor of the second cylinder C². The wheels L and M are change wheels, and the latter is mounted upon a stud P, fixed in the slot Q of the arm R, turning upon the stud S, on which the wheel N is mounted, and such arm is fixed by the studs T, passing through curved slots U. Thus to alter the speed of the cylinder C' wheels of different relative sizes are substituted for L and M.

The action of the drying-machine in the above-described arrangement is to thoroughly heat the fabrics and cause the waterproofing substances previously deposited to "run" and evenly coat the component fibers of the fabrics, and thus be absorbed by such fabrics.

I claim—

The combination of the heated cylinder C', the trough for the waterproofing material in which the cylinder revolves, the roller K, bearing upon the cylinder C', the cylinder C², which draws the fabric between the cylinder C' and the roller K, the gear-wheel O on the shaft of the cylinder C², and the interchangeable wheels M and N, interposed between the wheel O and a gear-wheel on the shaft of the cylinder C', one of the said wheels being mounted on a shaft which is supported in slots in the frame of the machine, substantially as set forth.

In testimony whereof I have hereunto set my hand in the presence of two subscribing witnesses.

THOMAS FERNELEY WILEY.
